UNITED STATES PATENT OFFICE.

CHARLES E. BELL, OF CHARLEROI, PENNSYLVANIA, ASSIGNOR OF ONE-HALF TO
THOMAS H. ROBINSON, OF DONORA, PENNSYLVANIA.

MINE-CAR CHECK LOCK.

Application filed August 20, 1924. Serial No. 733,168.

This invention relates to locking devices, and more particularly to a lock specially adapted for securing mine car checks such as commonly used by miners.

5 One of the main objects of the invention is to provide a check lock of simple and inexpensive construction which will securely hold the check in such manner as to effectually avoid its unauthorized removal. A 10 further object is to provide a lock in which the locking bolt is magnetically operated thus avoiding any possibility of releasing the check by means of a key or similar element. Another object is to provide a lock 15 so constructed as to effectually prevent release of the check by means of a strip of wire or other material inserted into the lock. Further objects will appear from the detail description.

20 In the drawings:—

Fig. 1 is a front view of the lock;

Fig. 2 is a back view;

Fig. 3 is a section taken substantially on line 3—3 of Fig. 1;

25 Fig. 4 is an inner face view of the back plate;

Fig. 5 is a plan view of a miner's check to be used in connection with the lock;

Fig. 6 is a side view of the locking bolt;

30 Fig. 7 is an end view of the bolt.

The body of the lock is formed of a front plate 1 and a back plate 2. The back plate is of approximately semi-circular shape, being slightly greater in extent than a semi-circle, and fits snugly into a similarly shaped flange 3 extending rearwardly from plate 1. This back plate is provided, in its inner face, with a recess 4 which co-operates with the inner face of front plate 1 to provide a slot 40 for reception of a check such as that shown in Fig. 5. The main portion of this recess increases inwardly in depth to within a short distance of a socket 5 provided in the upper portion of plate 2 for reception of the inner end portion of a locking member or bolt 6. This provides a depression 2^a at the inner side of check A when the latter is in the lock, and a shoulder 2^b adjacent to the lower edge of socket 5. In the event that an attempt is made to release the check by inserting a thin strip of material between the check and back plate 2, this strip of material 50 will follow depression 2^a so as to be deflected away from check A until it encounters

shoulder 2^b. As the upper portion 4^a of depression 4 is of just sufficient depth to snugly receive the upper portion of the check, the strip of material which encounters shoulder 2^b will be deflected upwardly thereby and, upon contact with the inner face of check A, will be turned back upon itself. This serves to effectually prevent the release of check A by inserting a strip of material between the check and back plate 2.

55 Locking bolt 6 is normally held in its inner or operative position by means of an expansion spring 7 mounted about stem 8 of the bolt and confined between a square shoulder 9 carried by the bolt and the outer end of a recess 10 extending from the inner 60 face of the front plate 1, shoulder 9 operating in this recess and fitting snugly therein. The nose 11 of bolt 6 has its inner end beveled at 11^a so that, when the check is 65 inserted into the lock it will displace the bolt or force it outwardly against the action of spring 7 until opening a in check A registers with socket 5, at which time the nose portion of the bolt will pass through 70 opening a into the socket thus securing the 75 check in the lock. As will be noted more clearly from Fig. 3, the cylindrical portion of nose 11 adjacent to shoulder 9 is of such length that, when the bolt is in locking 80 position with the end portion of nose 11 in socket 5, the cylindrical portion of the nose will extend to within a short distance of the inner face of back plate 2. This effectually prevents displacement of the bolt so as to 85 release check A by insertion of a thin strip of material between check A and plate 1, as this strip will strike the cylindrical portion 90 of the nose of the bolt and will be turned back upon itself. As will be noted from Fig. 3, the upper portion of check A is 95 beveled at a' so that when the check is inserted into the casing of the lock this beveled portion will engage between the beveled surface 11^a of nose 11 of the bolt and the inner face of back plate 2, thus forcing the lock outwardly until the check has been completely inserted at which time it will be secured by the bolt in the manner described. This permits ready insertion of the check 100 into the lock.

105 To release the check A it is, of course, necessary to move bolt 6 outwardly. To permit this to be done, the bolt is made of

magnetic material, the body of the lock consisting of plates 1 and 2 being made of any suitable or preferred non-magnetic material, such as brass or aluminum, though any other suitable non-magnetic material may be used for this purpose. A soft iron disc 12 is set into plate 1 in alignment and concentric with a bore 10^a extending from recess 10 and accommodating neck 8 of the bolt. To release the check an energized electro-magnet is placed against or closely adjacent to disc 12. As the body of the lock is of non-magnetic material, the lines of magnetic force will tend to collect at the central portion of disc 12 and to concentrate upon the neck of the bolt, pulling the bolt outwardly against the action of spring 7, thus releasing the check which will drop out of the lock or may be readily withdrawn therefrom. Preferably, though not necessarily, back plate 2 tapers in thickness, being thicker at its lower portion, so as to cause the lock to set at an angle to the side B of a mine car to which the lock is secured by riveting or any other suitable or preferred manner. For this purpose, front plate 1 is provided, at its lower portion, with laterally projecting ears 13 which receive rivets 14, these rivets also passing through the side wall B of the car.

As above indicated, and as will be understood, changes in details of construction and arrangement of parts of the invention may be resorted to without departing from the scope of the same, and I intend to include all such variations, as fall within the scope of the appended claims, in this application

in which a preferred form only of my invention is disclosed.

What I claim is:—

1. In a mine car check lock, a body provided with a slot for reception of a mine car check, and a spring pressed bolt normally projected across the slot, said bolt having its inner end portion beveled to permit the bolt to be forced outwardly by a check inserted into said slot, one side of the slot increasing in depth from the outer end of said slot to within a short distance of the bolt and providing a shoulder extending transversely of the slot in advance of the bolt.

2. In a mine car check lock, a body provided with a slot for reception of a mine car check, and a spring pressed bolt normally projected across the slot, said bolt having its inner end portion beveled to permit the bolt to be forced outwardly by a check inserted into said slot, said body being provided with a socket receiving the inner portion of the bolt and with a depression forming a shoulder extending transversely of the slot in advance of and adjacent to said socket.

3. In a mine car check lock, a body provided with a slot for reception of a mine car check, and a spring pressed locking bolt normally projected across the slot, the body being provided with a recess for reception of the bolt, said bolt being of magnetic material, and a disc of magnetic material secured to the body and closing the outer end of said recess.

In testimony whereof I affix my signature.

CHARLES E. BELL.
